DESIGN FOR AN EYEGLASS FRAME OR SIMILAR ARTICLE

Raymond L. Wells, Attleboro, Mass., assignor to
American Optical Company, Southbridge,
Mass., a voluntary association of Massachu-
sets

Application July 18, 1936, Serial No. 63,936

Term of patent 14 years

To all whom it may concern:

Be it known that I, Raymond L. Wells, a citizen
of the United States of America, residing at Attle-
boro, in the county of Bristol and State of Massa-
chusetts, have invented a new, original, and orna-
mental Design for an Eyeglass Frame or Similar
Article, of which the following is a specification,
reference being made to the accompanying draw-
ing forming a part thereof.

Fig. I is an enlarged perspective view of an eye-
glass frame or similar article embodying my new
design; and

Fig. II is a plan view of the mounting shown in
Fig. I.

The characteristic features of my design are
shown in full lines. The parts shown in dotted
lines are of conventional form.

I claim:

The ornamental design for an eyeglass frame or
similar article substantially as shown and de-
scribed.

RAYMOND L. WELLS.
